ELECTRIC SWITCHES

Albert Victor Waters, Perivale, Greenford, England, assignor to C. A. V. Limited, London, England

Application September 8, 1953, Serial No. 378,740

Claims priority, application Great Britain September 17, 1952

1 Claim. (Cl. 200—113)

This invention has for its object to provide in a simple form, an electric switch of the pull-push type adapted to serve also as an automatic thermally-operable circuit-breaker in the event of an overload.

A switch in accordance with the invention comprises an axially slideable and manually operable plunger, a contact piece carried by the plunger, a thermally-deformable contact component of the kind herein specified provided with a second contact piece, and means carried by the plunger for re-setting the said component after thermal deformation.

In the accompanying drawings:

Figure 1 is a sectional side elevation and Figure 2 an end elevation of a switch embodying the invention.

Figure 3 is a plan of the thermally-deformable contact component.

Referring to the drawings, a hollow body part *a* having therein a cylindrical bore, has slidably mounted in the bore a plunger *b* which at its outer end is provided with or is shaped to serve as a finger piece *c*. The "on" and "off" positions of the plunger are determined by a ball catch or catches *d* loaded by a spring *e* and adapted to engage recesses *f* in the bore of the body part.

At the inner end of the plunger is secured a contact piece *g*, and this is connected by a flexible metal strip *h* to a circuit terminal *i* carried by a part *j* which is secured to one end of the body part *a*.

The complementary contact piece *k* is formed on or secured to a flexible and elastic bi-metal component of the kind which requires to be re-set after thermal deformation, this component being secured to another circuit terminal *m* on the part *j* of the switch. In one convenient and known form this component consists of a rectangular piece of bi-metal sheet *n* (Figure 3) which is slotted to provide a tongue *o* lying between a pair of side parts, and is slightly bowed as shown in Figure 1, the contact piece *k* being formed on or secured to the free end of the tongue. When heated the tongue and side parts bend relatively to each other in opposite directions, with a flick-action, and so effect separation of the contact pieces

2

g, k, the tongue and side parts remaining in this condition on cooling.

To effect re-setting of the tongue and side parts of the thermally-deformable component after thermal deformation, and so restore them to their initial relationship, there is provided on the inner end of the plunger a striker *p* which on retraction of the plunger bears against the tongue piece and thereby causes the side and tongue parts of the component to spring back to their normal relative positions. Preferably the striker *p* is provided with a rubber or like button *q* which when the tongue piece is being re-set presses against an abutment *r* on the tongue piece.

To close the switch, the contact pieces are brought together by inward movement of the plunger. So long as the current then flowing through the switch is within a predetermined amount, the contact piece remains in mutual contact, and to open the switch the plunger is retracted. But in the event of an overload, the bi-metal component is thermally deformed and separation of the contact pieces is thereby effected automatically. Restoration of the component to its normal condition after cooling is effected by retraction of the plunger.

By this invention a combined manually operable switch and automatic circuit breaker is provided in a very simple form.

Having thus described my invention what I claim as new and desire to secure by Letters Patent is:

An electric push-pull switch which is adapted to serve also as an automatic thermally-operable circuit-breaker in the event of an overload, and which comprises in combination a body part, an axially slideable and manually operable plunger carried by said body part, a contact piece on said plunger, a thermally-deformable component of the kind which upon cooling after thermal deformation retains its deformed condition until subjected to a resetting operation, a second contact piece on said component, means for supporting said component so that the contact piece on said plunger can be brought into contact with the contact piece on said component by axial movement of said plunger in one direction, and thereafter separated from the last mentioned contact piece by axial movement of said plunger in the opposite direction as well as by thermal deformation of said component, and a striker carried by said plunger in a position where it can serve, during movement of the plunger in the direction for separating the contact pieces, to act on and re-set said component following thermal deformation of the latter.
